UNITED STATES PATENT OFFICE.

JACOB S. PEACOCK, OF LANCASTER, PENNSYLVANIA.

DESIGN FOR A PADLOCK-CASE.

SPECIFICATION forming part of Design No. 26,734, dated March 9, 1897.

Application filed November 4, 1895. Serial No. 567,951. Term of patent 7 years.

To all whom it may concern:

Be it known that I, JACOB S. PEACOCK, a citizen of the United States, residing at Lancaster, in the county of Lancaster and State 5 of Pennsylvania, have invented and produced a new and original Design for Padlocks, of which the following is a specification, reference being had to the accompanying drawing, forming part thereof, in which is shown 10 a face view of a padlock embodying my design.

The lock-case of my padlock is rectangular in general outline; but on the front or upper side there are wings projecting from the corners longitudinally of the case, the front or 15 upper edge of the wings being prolongations of the front or upper edge of the case. These wings are connected with the ends of the body of the lock by concave curves.

The shackle of the padlock comprises a bar 20 extending entirely across and parallel with the front or upper edge of the case, and said

bar has two arms extending to the case, one from the center and one from one end of the bar, while on the other end of said bar there is an outwardly-extending stud. 25

In the drawings, A designates the case; A', the wings; α , the ends of the body of the case, and α' the curves, connecting said ends and the wings.

B indicates the shackle-bar; b, the arm extending from the center of said bar to the case; b' , the arm extending from one end of said bar to the case, and b^2 the outwardly-extending stud on the other end of said bar. 30

What I claim is—

The design for the case of a padlock, substantially as shown and described. 35

JACOB S. PEACOCK.
